UNITED STATES PATENT OFFICE.

ALEXANDRE BOUILLON, OF LIEGE, BELGIUM.

METHOD OF LAYING TRAMWAY LINES.

Application filed September 21, 1925, Serial No. 57,694, and in Belgium September 26, 1924.

In the construction of tramway lines, there are two essential points which must be considered, namely: 1.—The line proper which comprises the rails and the supports.

5 2.—The covering of the road.

The primitive system of establishing a line consisted in laying the rails on wooden blocks commonly called sleepers.

This system is analogous to that in use 10 for the working of the large railway lines where it gives complete satisfaction as it has become general in the whole of the world. Its application to tramways, however, is not as successful. The railways are usually laid 15 on special chairs and the sleepers are placed on a thick layer of ballast; the rails, the sleepers and all the accessories remain uncovered and are always visible; the drainage of the water is always assured. On the 20 contrary tramway lines are nearly always laid in paved roads of highways used by ordinary vehicles and must undergo all kinds of destructive effects caused by the latter; the laying down of sleepers is not effected 25 very carefully; the rails, their supports and all the line accessories are covered by a covering layer which makes them invisible and inaccessible without previous demolition; and they are, as a rule, if not always, laid 30 on a layer of ballast of insufficient thickness; they are sometimes laid simply on the ground.

After a little while the foundation or the 35 sleepers sinks into the ground and the covering of the road is broken up; from this results a defective traffic circulation and very considerable maintenance expenses.

When a line laid on sleepers is carefully 40 considered it is found that the paving stones of the road rest alternatively on the sleepers and on the ground in the intervals between the former; the paving stones which rest on the sleepers could not sink down but those which are on the intermediate spaces between the sleepers rest on a soil capable of 45 being compressed and being deformed and which favours their sinking in. By reason of this circumstance there are formed very frequently, if not always, inside the lines 50 undulations in the pavement which are very prejudicial to the traffic of ordinary vehicles and which make frequent repairs necessary.

In order to do away with this inconvenience the rails have been placed either 55 on cast iron chairs or on wooden blocks fixed

to the sleepers, the results have not been sufficiently satisfactory, the less so, as this system entailed inconveniences which did not appertain to the simple line. 60

The running of the cars on rails resting on concrete sleepers is hard and sonorous.

The want of elasticity of these sleepers produces a very considerable undulatory wear of the riding surface of the rails. When 65 there is an undulatory wear the running is very disagreeable and produces a grinding sound.

This undulatory wear can only be made to disappear by machining or grinding the 70 rails. This is an expensive work which, moreover, has as a result a more rapid wear of the rails.

The undulatory wear has a repercussive effect upon the tires of the wheels of the 75 cars which, after a certain time must be trued on the lathe.

From the foregoing it may be concluded that a tramway line must possess the following characteristics:— 80

1. Elasticity. In order that it may possess this feature the rails must rest on supports placed at certain distances apart; these supports must themselves, show a certain elasticity; iron, stone, concrete and any 85 similar material cannot be used for this purpose. Wood is most suitable for the purpose.

2. As little noise as possible. For this construction materials of the least resonancy 90 must be used, and if possible, every device must be adopted which reduces this resonancy. 3. Stability.—For this purpose it must be laid on a rigid foundation which cannot be deformed. 4. The covering of the 95 road must be constructed of hard materials which offer a great resistance to wear. 5. This covering must be firm, that is to say, it must be laid on a rigid foundation which cannot be deformed and which forms one 100 body with the foundation of the line.

The object of the present invention is to provide a method of laying a tramway line which possesses the qualities above referred to. 105

The accompanying drawings show the method of laying a tramway line in accordance with this present invention.

In the drawings. Figure 1 represents a cross-section of a tramway line laid on a 110 paved road.

Figure 2 represents a longitudinal section

of Figure 1 on a smaller scale, in the direction of the axis of the rail.

Figure 3 represents a plan view of Figure 1.

5 Figure 4 represents a cross section of a tramway line according to a modification and laid in a paved road.

Figure 5 represents a longitudinal section of Figure 4 on a smaller scale, in the direction of the axis of the rail.

Figure 6 represents a cross-section of a tramway line laid on an asphalted road.

Figure 7 represents a longitudinal section on a smaller scale of Figure 6, in the direction of the axis of the rail.

Figure 8 represents a plan view of Figure 6.

Referring to the drawings, the rails, such as 1, are laid on wooden blocks 2 resting on 20 a concrete foundation 3, which may be reinforced concrete or otherwise, with the interposition of a suitable layer of material or of a resilient plate 4.

The wooden blocks 2 are thus enclosed in 25 the concrete foundation 3 with the exception of one side, where they are engaged by a wedge 5, the length of which is such that if for any reason it should become necessary to plane down, remove or renew the block 2, the wedge 5 could be removed and the block 2 could be shifted by a sufficient amount to be itself removed without destroying the concrete of the foundation.

The foundation 3 is to be of such a thickness as to correspond to the resistance of the ground; if necessary, it can be reinforced; as indicated, for instance, by Figures 4 and 35 5 by iron inserts such as 6.

This foundation extends for the length 40 of the road occupied by the track.

The rails 1 are kept at the normal distance from each other by iron rods 7; they have applied on both sides either bricks 8 or concrete, so as to establish a substantial 45 and regular abutment for the paving stones 9; they are fixed to the blocks 2 by means of wood screws 15 with flat heads.

The line rests on wooden blocks 2 which 50 serve the same purpose as the sleepers, in the line on sleepers; as a matter of fact, the sleeper, which serves as support for the two rails becomes, in the event of a sinking of one of its ends a lever, which causes the raising up of the other end; from this results 55 an upsetting of the line, which breaks up the covering material all over the length; the sleeper, therefore, makes the two rails as if they formed one piece one with the other, whilst the blocks 2 make the rails absolutely 60 independent one from the other and, even assuming that one block might sink, the one opposite it will not be affected thereby in any way and the deterioration of the line is localized to the neighbourhood of the block 65 which has given way.

Against this the objection may be brought forward that sleepers serve for maintaining the distance between the rails, but the blocks 2 enclosed in concrete 3 can effect this purpose in just as complete a manner. If provision has been made for the distance rods 7, this is done in order to secure for the rails a greater rigidity and thus to diminish, as far as possible, the deteriorations which occur by reason of their susceptibility of motion.

The line on blocks is elastic; this elasticity is largely increased by placing under the blocks 2, the resilient plate or layer 4.

It will not be very noisy because, apart 80 from the wooden blocks 2, the resilient plate or layer 4 on which they rest reduces the resonance considerably.

Two blocks represent a cubic measure of 85 wood equivalent approximately to one third of that of a sleeper, from which results a very substantial saving in the first cost.

The wedge 5 may consist either of new 90 soft wood or of wood already previously used (old sleepers, for instance) pavement waste, or bricks.

The concrete foundation 3 will give to the line a perfect stability; its thickness will, of course, be proportionate to the resistance of the soil, so that no sinking whatever can occur.

The foundation concrete may consist, for instance, of fresh granulated slag from blast furnaces or of other suitable material, to which is added at least one-tenth of cement; the cement may be substituted by two-tenths of freshly slaked lime.

The concrete thus prepared sets rather 100 rapidly and becomes exceedingly hard and resisting; it has, moreover, the enormous advantage of a very low cost.

If necessary the concrete may consist of 105 unwashed ashes from zinc works, to which are added cement and lime, as in the case of fresh granulated slag from blast furnaces.

The road covering (see Figures 1 and 4) 110 will consist of paving stones, such as 9, of sandstone, porphyry, quartzite or other similar materials. This covering will not be subject to deformation and will be very firm, as it rests on a foundation 3 of solid and rigid concrete, which also is not subject to deformation, with an intermediate uniform elastic and non-compressible layer 10 of gravel sand of from 4 to 5 cm. thickness.

This elastic layer of sand will, moreover, have the effect of enabling the paving stones 115 to resist perfectly the shocks of wheeled traffic and prevent their destruction.

With this system it is possible, or even necessary, to make use of low paving stones; that is to say, such as of 13 cm. height instead of paving stones of 15 cm. height, because, when using paving stones of 15 cm., those 120 125 130

placed against the rails would rest partly on the rail foot and partly on the layer of sand and there would then exist a tendency for them to be turned over or to break; in 5 either of these circumstances they would cause the deterioration of the adjacent paving.

If the covering is in asphalt (11) see Figures 6 and 7, or in paving stones of very 10 small dimensions, the system represented in Figures 6, 7 and 8 is to be employed.

In this arrangement the foundations 3 in concrete are continued under rails 1 in the shape of longitudinal sleepers 13: they comprise 15 the grooves necessary for the placing of an elastic layer 4 and of the block 2 and an empty space 14 under the rails 1 which is indispensable for their free bending and their elasticity. The foundations are connected 20 by a layer of concrete 12 having parallel to the rails 1 suitable intervals for placing the bricks 8, adjacent to the web of the rails, and the paving stones such as 9 the purpose of which is to separate the layer 25 of asphalt 11 from the rails 1 and to allow of easy access to the devices for fixing the rails 1 to the blocks 2.

It is to be understood that the drawings serve only as showing an example of construction and that other details may be given for instance to the concrete foundation and to the elastic layer, without the essential part of the invention being departed from.

The first cost is not very high and is approximately 30 equivalent to that of the line placed on longitudinal ballast sleepers.

The maintenance of the line and of the road covering is practically nil or at least reduced to the strictest minimum.

Having now particularly described and ascertained the nature of my said invention,

and in what manner the same is to be performed, I declare that what I claim is:

1. A tramway road-bed comprising a concrete foundation member having a rectangular recess formed in its top, said recess having side and end walls of unbroken area and a bottom of unbroken area and having its top open for substantially its full area and being of different depths, having a deep 45 portion and a shallow portion, in combination with an elastic cushioning layer arranged in the deep portion, a wooden block located in the deep portion entirely and resting on said cushioning layer and supporting 50 a tramway rail, and a wedging member extending in said shallow portion and bearing against said wooden block and an opposed face of one of the walls of said recess, whereby removal of said block and wedge in any 55 direction other than vertically upward is prevented.

2. A tramway road-bed comprising a concrete foundation member having an oblong recess having its top open for substantially 65 its full area and being defined by an unbroken, in a horizontal plane, wall of concrete, in combination with a wooden block of less length than said recess snugly fitting therein, and wedging means bearing against 70 an end of said block and the opposed end wall of said recess to hold said block against substantial movement in said recess, said block and wedge being introduced into said recess through the open top thereof and in 75 assembled relation therein lying between vertical planes defining the vertical profile of the said recess.

In testimony whereof, I have signed my name to this specification at Antwerp, Belgium, this 9 day of September, 1925.

ALEXANDRE BOUILLOUN.
